HAIR CUTTING TOOL

Harold Plough, Aurora, Ill.

Application May 24, 1957, Serial No. 661,476

10 Claims. (Cl. 7—14.1)

The invention relates to improvements in hair cutting tools and is particularly concerned with a novel cutting tool of a type that is very useful in shaping, thinning and styling hair on the human head.

Tools of this character generally embody the characteristics of a conventional straight razor and they include a long straight handle portion and a head portion that is formed to receive, removably mounted therein, a single edge razor blade. The tool disclosed herein has its blade carrying head portion disposed angularly relative to the handle portion to facilitate its use and the tool may be safely used without a blade guard. However, it preferably is provided with a novel bumper guard that can be easily removed from or attached directly to the razor blade and, when attached, the guard is movable relative to the cutting edge of the blade so as to be carried automatically out of the path of said cutting edge while the blade is in use. When the tool is not in use, one edge of the attached guard will project beyond the cutting edge of the blade so as to prevent inadvertent cutting of any matter or thing should it be carried into the region of the blade edge.

Known hair cutting tools of the character to which this invention pertains are difficult to hold in the hand during the between cutting operations. Otherwise stated, prior known tools require that they be gripped firmly at all times to prevent them from slipping in the hand and cutting the user. This characteristic of known cutting tools prevents the user from performing any one or all of the many other acts required during a hair-dressing operation. For example, it is important and necessary to comb and cut in sequence during a styling, or to apply a bobby pin to certain areas of the hair. This usually is best accomplished by using the same hand used for holding the cutting tool. This necessitates tightening of the grip on the tool in order to hold a comb, thus slowing down the operator's technique, because slipping of the tool in the hand could cause possible injury. The present cutting tool includes novel structure, preferably in the form of a resiliently flexible loop or loops on the handle, either one of which may be engaged around one finger of the hand so as to automatically turn the tool in the hand and thereby prevent the tool from sliding even though the grip thereon may be entirely relaxed.

Hair thinning, cutting or shaping usually requires that some or all of the hair in certain areas of the head be cut to a length of about 3", while in other areas it may be cut to about 4" or perhaps 5". Much time is saved by the user of the present tool, which includes novel means to determine the length to which the hair is to be reduced. This means preferably comprises the provision of a measuring scale on the tool handle to permit its use as a measuring device.

It is, therefore, an object of the invention to provide a novelly constructed, well balanced, hair cutting tool.

Another object is to provide a hair cutting tool that is properly shaped to fit the hand.

Another object is to provide a hair cutting tool of such

2

shape as to prevent an operator from cutting too close to the head.

Another object is to provide novel means to automatically turn the blade away from its cutting direction when released by the hand.

Another object is to provide a hair cutting tool so constructed as to permit safe use of tool with unguarded razor blade.

Another object is to provide a hair cutting tool of the character described which includes novel means to detachably secure it to the hand so as to prevent it from falling or slipping therefrom.

Another object is to provide a hair cutting tool, of the character having a razor type blade mounted therein, with a novel easily removed or attached floating bumper guard for the blade.

Another object is to provide a cutting tool with a measuring scale.

With the foregoing and such other objects in view, which will appear as the description proceeds, the invention consists of certain novel features of construction, arrangement and combination of parts hereinafter fully described, illustrated in the accompanying drawings, and particularly pointed out in the appended claims, it being understood that various changes in form, proportion, size and minor details of the structure may be made without departing from the spirit of the invention.

Referring to the drawings in which the same characters of reference are employed to identify corresponding parts:

Figure 1 is a perspective view of one embodiment of the hair cutting tool, showing it held loosely in a hand.

Figure 2 is a side elevational view of the cutting tool.

Figure 3 is a top edge view of the cutting tool head portion and a fragment of the handle portion thereof.

Figure 4 is an enlarged detail sectional view taken on line 4—4 of Figure 2.

Figure 5 is a fragmentary elevational view of a razor blade of the character used in the tool herein disclosed.

Figure 6 is an enlarged perspective view of the novel bumper guard.

Figure 7 is a perspective view of another embodiment of the tool.

Figure 8 is an elevational view of the handle portion of the tool shown in Figure 7.

Referring to the accompanying drawings, the hair cutting tool shown in Figures 1 through 5 is preferably fabricated from a shaped length of sheet metal stock suitably folded upon itself longitudinally to provide a double wall structure and comprised of an elongated flat handle portion 11 and a flat blade-holding head portion 12. The plane of the head portion 12 preferably is disposed at an angle to the plane of the handle portion 11, as is perhaps best illustrated in Figure 3, so as to facilitate use of the device. As shown, the head portion 12 is considerably narrower in its over-all width than the width of the adjacent connected portion of the handle 11 so as to provide an inwardly offset edge 13 substantially co-extensive with the length of the head portion.

A conventional type of single edge razor blade 14 is slideably mounted in the head portion 12, as is perhaps best illustrated in Figure 4, so as to dispose its cutting edge 15 substantially in alignment with the edge 16 of the handle portion 11. The blade 14 has end recesses 17 which are utilized, in the present disclosure, to loosely retain a bumper guard 18, best shown in Figure 6, in position on said blade.

The bumper guard 18 comprises a strip of sheet metal having width that is slightly greater than the width of the exposed portion of the cutting blade 14 and a length corresponding substantially to the length of said cutting blade. The bumper guard is formed on each of

its ends with an integral attaching or clip portion 19 which is adapted to be engaged in a related one of the end recesses or notches 17 so as to hold the bumper guard 18 substantially in the position illustrated in Figure 4 with respect to the blade 14.

It should be noted that each of the clips 19 on the guard 18 have one of their side edges 21 cut back inwardly of its ends so as to permit rocking motion to be accorded the bumper guard 18 about the engagement of the offset edges 21 of the clips 19 with the related edges of the engaged recesses 17. This construction is such that although the bumper guard is retained in place on the blade until such time as its removal is desired, it is free to rock into and out of parallel with the plane of the blade. When parallel to, or in substantial face to face contact with the blade, the guard will normally prevent inadvertent contact of the edge of the blade with any object or thing which might be damaged or injured thereby. The bumper guard may, however, rock in such direction that the protruding free forward edge 22 thereof is carried outwardly away from the cutting edge 15 during the hair cutting operation to thereby not interfere in any manner whatsoever with the usual and normal functioning of the blade.

Inasmuch as it is frequently necessary to determine the intended length of the hair preliminary to or while the cutting operations are proceeding, it is most advantageous to provide, on the cutting tool, measuring means preferably in the form of the scale calibrations 23 best shown in Figure 2. As illustrated, the calibrations are representative of five 1" scale markings and it should be quite apparent that an operator may easily and quickly obtain any required measurement by the simple expedient of thrusting the extreme end of the head portion 12 against the scalp and combing the hair outwardly along or adjacent to the cutting tool. This obviates the need for the use of a separate measuring device.

Owing to the necessity, during the process of cutting, thinning or trimming the hair on a human head, to frequently comb the hair or otherwise perform functions not specifically requiring the use of the cutting tool, the grip on the cutting tool sometimes relaxes to a degree that would permit said tool to slide in the hand with resultant injury to the operator or patron. In order to obviate this undesirable occurrence and furthermore to enable the operator to retain the cutting tool in the hand while using said hand to pin, comb, or otherwise perform unrelated operations on the hair, the cutting tool is provided with novel means to prevent displacement of the same.

One such means is perhaps best illustrated in Figures 1 and 2, where it will be observed the free end of the handle portion 11 is provided preferably with a plurality of mutually spaced apart openings 24, preferably on the folded margin thereof, and through which are extended the free ends of loops 25. Either or both of these loops may consist of suitable lengths of rubber, elastic cord, or other pliable but wear resisting material. The free ends of the loops 25 are anchored within the handle portion 11 in any suitable manner. In use, the operator will insert the little finger, preferably, of the hand through either one or the other of the loops 25. The engaged loop is then twisted, in the manner illustrated in Figure 1, so as to tension the elastic loop about the finger and when the cutting tool is held substantially in the position illustrated in Figure 1 it cannot slip out of the operator's hand even though the fingers thereof are substantially relaxed and disengaged therefrom, as shown.

In the embodiment illustrated in Figures 7 and 8, the tool is substantially like the tool previously described and like numbers are used to identify corresponding parts. In this disclosure, however, the handle portion 11 is provided with means to facilitate adjustment of the single

elastic cord 25a provided thereon. As shown, one wall of the handle is formed with a slot 26 spaced inwardly from its free end and preferably disposed at an angle of about 45° so as to receive one knotted end of the elastic cord 25a.

A plurality of mutually spaced slots 27 also are provided in the said wall of the handle portion 11 inwardly of the slot 26 and these slots also are disposed at an angle of about 45° in a direction opposed to the angle of slot 26. The other knotted cord end is selectively engaged in either one of the slots 27, the selection of the slot engaged being determined by the operator so as to adapt the holding means for cooperation with various sizes of hands. In the Figure 7 disclosure, the cord is engaged around the third finger in the same manner as described with reference to the Figure 1 disclosure. Because of the twist in the finger engaged loop on the third finger, the cutting tool automatically turns away from the relaxed fingers or the head of the patron while said fingers are engaged in other holding functions.

As many possible embodiments may be made in the invention, and as many changes might be made in the embodiments set forth above, it is to be understood that all matters hereinbefore set forth or shown in the accompanying drawings are to be interpreted as illustrative and not in a limiting sense.

Having thus described the invention, what is claimed as new and desired to be secured by Letters Patent is:

1. A hair cutting tool of the character adapted to be held in the hand comprising a one-piece holder including a handle portion and a head portion, said head portion being disposed at an angle to the handle portion and having one edge thereof offset inwardly from the complementary edge of the handle to define an edge recess, a razor blade carried by said head portion and filling the recess, said blade having its cutting edge substantially coplanar to the said edge of the handle, a bumper guard loosely mounted on the portion of the blade within said recess, said guard having an edge substantially co-extensive with and parallel to the cutting edge, and means to prevent slipping of the tool when the holding grip thereon is relaxed.

2. A hair cutting tool of the character adapted to be held in the hand comprising a one-piece holder including a handle portion and a head portion, said head portion having one edge thereof offset inwardly from the complementary edge of the handle to define an edge recess, a razor blade carried by said head portion and filling the recess, said blade having its cutting edge substantially coplanar to the said edge of the handle, a bumper guard loosely mounted on the portion of the blade within said recess, said guard having an edge substantially co-extensive with and parallel to the cutting edge, and means to prevent slipping of the tool when the holding grip thereon is relaxed.

3. In a hair cutting tool of the type adapted to be held in the hand, said tool comprising an elongated handle portion and a head portion on one end of the handle portion and disposed at an angle relative to the plane of the handle, measuring scale markings on said handle portion, a cutting blade carried by the head and having an exposed cutting edge, a guard loosely mounted on said blade, said guard having an edge lying in the plane of said cutting edge and adapted normally to prevent unintended contact with the cutting edge, said guard being movable relative to said blade to permit said cutting edge to perform its function when the tool is in use, and means on the handle portion to positively secure the handle to a hand so as to prevent slipping thereof.

4. In a hair cutting tool of the type adapted to be held in the hand, said tool comprising a head portion and an elongated handle portion, a cutting blade carried in the head portion, and resilient means on the handle engageable with a finger on a hand to prevent slipping of the tool when held loosely.

5. In a hair cutting tool of the type adapted to be held in the hand, said tool comprising an elongated handle portion and a head portion on one end of the handle portion and disposed at an angle relative to the plane of the handle portion, a cutting blade carried by the head portion, a finger engaging resilient loop carried by said handle portion, and means to adjust said loop so as to adapt it for engagement with a selected finger of a hand holding said tool, said loop being twisted in a manner to move the tool and carry the cutting blade out of cutting position when the grip on the handle portion is relaxed.

6. In a hair cutting tool of the type adapted to be held in the hand, said tool comprising an elongated handle portion and a head portion on one end thereof, a cutting blade carried by the head portion, a plurality of slotted openings in the handle portion, and an elastic cord engaged at its ends in selected openings, said cord defining a loop adapted to be engaged around a finger of a hand gripping the cutting tool and the engaged loop being twisted and tensioned so as to carry the cutting tool into an ineffective position when the grip on the handle is relaxed.

7. A hair cutting tool of the character adapted to be held in the hand comprising a one-piece holder including a handle portion and a head portion, said head portion having one edge thereof offset inwardly from the complementary edge of the handle to define an edge recess, a razor blade carried by said head portion and filling the recess, said blade having its cutting edge substantially coplanar to the said edge of the handle, and a bumper guard loosely mounted on the blade within said recess, said guard having an edge substantially coextensive with and parallel to the cutting edge.

8. A hair cutting tool of the character adapted to be held in the hand comprising a holder including a handle portion and a head portion, said head portion being dis-

posed at an angle to the handle portion and having one edge thereof offset inwardly from the complementary edge of the handle to define an edge recess, a razor blade carried by said head portion and filling the recess, said blade having its cutting edge substantially coplanar to the said edge of the handle, and a bumper guard loosely mounted on the portion of the blade within the recess.

9. A hair cutting tool comprising a rigid one-piece holder including a handle portion and a head portion, 10 said head portion being substantially U-shaped in section, a blade having one of its edge margins telescoped into said U-shaped head portion and a cutting edge on its other edge, a guard plate on one face of the exposed portion of said blade, a mounting clip at each end of the 15 plate and engageable with an end edge of the blade to detachably secure the guard to the blade in a manner to permit limited rocking movement between the guard and blade, said guard having an edge substantially co-extensive with the cutting edge.

10. A hair cutting tool comprising a rigid holder including a handle portion and a head portion, a blade having one of its edge margins mounted in the head portion and a cutting edge on its other edge, a guard plate on one face of the exposed portion of said blade having 25 an edge substantially coplanar with said cutting edge, and means on the opposed ends of said guard plate and adjacent to its other edge engageable with the blade for detachably securing the guard directly to the blade in a manner to permit limited rocking movement between the 30 guard and blade.
